POLISHING MACHINE

Filed Feb. 6, 1926

UNITED STATES PATENT OFFICE

ROBERT F. GIBNEY, OF HACKENSACK, NEW JERSEY

POLISHING MACHINE

Application filed February 6, 1926. Serial No. 86,479.

My invention relates to polishing machine, particularly suitable for the polishing of barrels and caps used in the manufacture of fountain pens and mechanical pencils.

The object of the invention is to provide a machine which is simple in construction, easy to operate and which will permit the polishing of surfaces of varying periphery with a substantial cylindrical buff and which will eliminate ridges or rings that may be in the article before it is being polished.

Another object of the invention is to provide a machine that will permit adjustment for the wear of the buff.

A still further object of the invention is to so arrange the holders for the object to be polished that the velocity of the buff tends to force the object on to the holder.

In the appended drawing, Figure 1 is a vertical section through the machine embodying my invention on line 1-1, Figure 2, and

Figure 2 is a top plan view.

Referring to the drawing, 3 is a frame which is preferably in the shape of an angle, the upright portion 4 of which is provided with guide-ways 5 while the horizontal portion 6 thereof has suitable lugs 7 for securing it to a bench. The horizontal portion 6 and the upright portion 4 of the frame 3 are reinforced by ribs 8.

A bed 9 provided with a depending portion 10 is mounted to slide in the guide-ways 5 of the frame 3. The movement of the bed is controlled by a screw 11 threaded into the frame 3 and connected to a lug 12 of the depending portion 10 of the bed. The depending portion 10 of the bed carries a vertical shaft 12 to which shaft is keyed a rotary table 13. The rotary table 13 carries a beveled gear 14 which is in mesh with a beveled pinion 15. The said pinion is constrained to revolve with a shaft 16 mounted on the bed 9. The shaft 16 also carries a loose pulley 17 provided with a clutch face 18 and a clutch 19 is provided on the shaft which is constrained to rotate with the shaft. A lever 20 mounted on the bed 9 controls the motion of the clutch 19 on the shaft 16 and whereby the loose pulley may be coupled

or uncoupled from the said shaft 16. To retain the clutch 19 in either position suitable means are provided on a lever 20 and a bed 9.

The rotary table 13 carries a plurality of posts 21 disposed near the outer periphery of the table. Each of the posts has a reduced cylindrical portion 22 which engages a corresponding opening 23 in the table. Each of the posts 21 is locked to the bed by means of a screw 24. See Figure 1. Each of the posts also carries an article holder or mandrel 25 fitted into a corresponding hole in the post and secured thereto by a screw 26.

As will be seen from Figure 2, the mandrels in the posts are disposed at an angle to the radial line of the table, and this angle may be varied by means of the said screws 24. A cylindrical buff 27 shown in Figures 1 and 2 in dots is revolved in a vertical plane in the direction indicated. The mandrels carrying the objects to be polished move toward the buff in the direction as indicated in Figure 2. As shown in Figure 2, the mandrel over the buff in said figure carries a fountain pen barrel indicated in dash and dotted lines. As the buff strikes the barrel, the friction forces the barrel on to the mandrel as it revolves it on the mandrel.

Furthermore, the buff engages the barrel on the mandrels obliquely to the axis of the barrel, that is, the axis of the article and the directrix of the cylindrical surface of the buff form an acute angle which decreases in size as the article passes over the buff. In consequence, the resultant force of this acute angle causes the article to move on to the holder. Due to this angular engagement of the article with the buff, the cutting or polishing line on the buff on the article is at an angle to the axis of the article, thereby eliminating ridges in the surface of the article that may have been formed during the grinding or polishing.

As the buff wears, the bed 9 can be lowered by means of the screw 11, thus compensating for wear of the buff. To retain the bed 9 rigid with the frame 3, lock screws 28 are provided in the frame 3 at the guides as shown in dotted lines in Figure 2.

I claim:

1. In combination a cylindrical buff revolving in a vertical plane, a table revolving in a horizontal plane, article holders on said table disposed at an angle to the radial line of the table, and means for varying the angle of the holders with the radial line of the table, said holders supporting the articles so that the same are free to revolve thereon and to move outwardly, the articles being prevented from moving outwardly while being rotated by the buff by the angular relation of the holders with the buff at the time of contact of the articles with the buff.
- 15 2. In combination a cylindrical buff revolving in a vertical plane, a table revolving in a horizontal plane, stationary mandrels disposed in a horizontal plane and carried by said table, and means for adjusting the angular relation of the mandrels with the radial line of the table, said mandrels adapted to support the fountain pen barrels or caps, so that the same are free to revolve or move outwardly thereon, the caps or barrels being prevented from moving outwardly on the mandrels when actuated by the buff, by the angular relation between the buff and the mandrel as the mandrel passes the buff.
